METHOD OF FORMING MICA INSULATED SPARK PLUGS

Filed Dec. 7, 1928

UNITED STATES PATENT OFFICE

HECTOR RABEZZANA, OF FLINT, MICHIGAN, ASSIGNOR TO A C SPARK PLUG COMPANY, OF FLINT, MICHIGAN, A CORPORATION OF MICHIGAN

METHOD OF FORMING MICA-INSULATED SPARK PLUGS

Application filed December 7, 1928. Serial No. 324,513.

As indicated by the above title, the present invention, in its specific aspect, relates to spark plugs; and it has particular reference to a method or process of producing a spark plug of that type in which mica, or the like, is used as an insulating material. It relates also to a novel and durable spark plug formed by said method or process; and it is a particular object of this invention, using annular 5 laminæ of mica or other suitable material, assumed to be in the form of "washers," to produce a conduction unit comprising a compact, durable, and solid body disposed about a central conductive element,—such as a tension- 10 able rod or wire, threaded at one end, and serving as an electrode permanently sealed against leakage.

The present invention involves, in a preferred embodiment, means and methods, of securing annular laminæ, or the like, under a predetermined axial compression,—weakened portions of exterior metallic elements, comparable with those described in my Patent No. 1,609,735, granted December 7, 1926, but differing therefrom in form, relationships and function, being so collapsed as to buckle or bulge inwardly, after the compression of the mica, or its equivalent, by a pressure applied axially of the mentioned tensionable element; and, in case electrical or other heating is employed in softening and/or inwardly expanding the mentioned weakened portion, this invention may utilize further lateral and longitudinal pressures which result from the 20 contraction of said weakened portions upon the associated metallic or other tensionable members during a subsequent cooling to normal temperature,—the result being an insulated unit whose compactness and impermeability to gases are exceedingly permanent and reliable.

Notwithstanding its easy cleavage in parallel planes and because of its great resistance to flame and to sudden temperature changes, as well as normal acid-resisting qualities which render it substantially impervious to engine gases, being a poor conductor of both heat and electricity, mica is a very desirable material for use as insulation in the spark 30 plugs of internal combustion engines,—espe-

cially in high speed and high compression engines; and it is accordingly a general object of this invention to provide both improved spark plugs and an improved technique in the utilization of mica in insulation. 55

Heretofore, mica insulators have sometimes been made by threading a quantity of mica "washers" upon a central wire member, a metallic shell being externally shrunk thereon and insulated by a mica sleeve surrounding the central wire,—the "washers" being compressed by suitable tools and held by a nut or end piece screw-threaded to the central wire; but that arrangement has been found subject to looseness and consequent 60 leakage, by reason of the unavoidable expansion and contraction of the external metallic parts while in use upon an engine; and it has provided no permanently gas-tight joints to seal the insulator from leakage,—depending 65 entirely upon the mentioned screw-threaded end piece or nut; and, although a mica assembly so built up about a central wire has sometimes been ostensibly sealed by cementing (as well as by the mentioned shrinking 70 of a metallic shell thereon) such assemblies have been observed to deteriorate in time by reason of the engine action and the mentioned 75 expansion and contraction of the metallic parts; and it is accordingly an object of this 80 invention, recognizing that mica possesses great flexibility, elasticity, and toughness, and is thereby particularly adapted to be compressed to a compact and solid mass formed from a number of initially separate 85 discs, to overcome the difficulties heretofore encountered,—said difficulties being herein attributed to the lack of proper means for holding the mica discs or "washers" in a compact body and with proper sealing joints 90 surrounding a central tensionable element such as the mentioned wire or a suitable rod or tube as required in spark plug insulation.

Other objects of this invention, including 95 a novel method of permanently securing a stop or clamping element upon a tensionable rod, with or without interposition of a tubular element, said stop or clamping element being initially provided with an annular groove so positioned as locally to reduce the 100

cross-sectional area thereof and provide a weakened section which is adapted to bulge inward under a suitable application of pressure and with or without a concurrent flow of electricity through said reduced section, to soften the same, may best be appreciated from the following description of illustrative embodiments of this invention, taken in connection with the appended claims and the accompanying drawing.

10 Fig. 1 is a general view, with parts broken away to a median plane, showing a so-called two-part spark plug produced in accordance with the principles of this invention.

15 Fig. 2 is a longitudinal sectional view, taken substantially as indicated by the line 2—2 of Fig. 1, but including only an inner electrode organization,—to which the present invention is more particularly directed.

20 Figs. 3—6 are respectively diagrammatic sectional views taken similarly to Fig. 2, but illustrating successive steps (and some optional features) in the production of a spark plug such as that shown in preceding figures.

25 Fig. 3 shows relationships before compression.

Fig. 7 is a detail view, upon a large scale, corresponding to an upper portion of Fig. 6,—to aid in the visualization of uniting effects which are hereinafter described.

30 Fig. 8 is a bottom plan view of the spark plug shown in Fig. 1, better to disclose one advantageous form of outer electrode or sparking element.

35 Fig. 9 is a sectional view, corresponding to the lower portion of Fig. 1 but showing an alternative type of outer electrode or sparking element.

40 Referring to details of that embodiment of the present invention chosen for purposes of illustration, it will be understood that, in the preparing and "dressing" of mica for use in the practice of this invention, so-called "books" of mica are split in a known manner 45 into sheets of suitable thickness, so-called "washers" being punched from the mentioned sheets; but not all steps of the selected embodiment of the present invention are deemed to be in need of illustration or explanation.

50 In Fig. 3, a central wire or rod 15 is shown as having been provided, at its lower end, with an enlarged stop element in the form of a head 16,—suitable to serve as a substantially flat and upwardly facing shoulder for a mica assembly; and a first insulating element or mica washer layer 17 is assumed to have been placed upon the central rod or wire 15. An insulating sleeve 18, which may 55 have been formed of a suitable composition or from rolled mica, may have been rolled upon a suitable arbor (not shown) or it may now be disposed upon the wire or rod 15, a second insulating unit or assembly 19, shown 60 as a layer of mica washers having a slightly

larger central opening, being added by slipping the same over the sleeve 18; and a tube 20 may then be pressed into place upon the sleeve 18. If employed at all, the mentioned arbor may be removed as the central wire or rod 15 is forced into the sleeve 18; after which bushing or special metal shell 21, shown as provided with a kerf or groove 21', separating a non-circular head portion 21a thereof from a circular threaded portion 21b, is placed over the tube 20,—said shell being preferably slightly longer than said tube and so reduced in thickness by kerf 21' as to provide, inwardly thereof, a weakened section 21c, having a relatively high resistance to electrical current by reasons of its limited cross-sectional area. Mica-protective tube 20 may be formed of copper.

65 The assembled or partially assembled unit may then be placed in a suitable press or so-called welding machine, as represented by suitable formed and oppositely disposed die or pressure elements 22, 23 adapted to apply to the mentioned parts a suitable pressure in the general direction of the axis of wire or rod 15; an electrical or other means (as symbolized by a plus sign and a minus sign in Figs. 3, 4 and 6) may be used previously or simultaneously to heat the shell 21 or the weakened section 21c to a red or other suitable temperature of slight plasticity,—adapting the same to so collapse, under continued or subsequent endwise pressure, that the wall of the shell buckles or bulges inwardly in the mentioned region,—somewhat 95 as indicated at 24, Fig. 4.

70 The described method will be seen to provide an annular rib or bead, inwardly projecting about the sleeve 18 and/or the tube 20; and the foregoing operations are presumably carried to the point of forcing and deforming the said tube inwardly, at the same time fusing and practically forming a weld between the shell 21 and the tube 20. This operation, diminishing kerf 21', may incidentally provide a similar bulge 25 upon the tube 20,—which will press and extend into the mica sleeve 18, forcing the latter very tightly to embrace the rod or wire 15 and permanently exerting a circumferentially bearing pressure which is adapted substantially to close any porous voids in the sleeve 18 or between the other contacting surfaces,—the shell or bushing 21 being optionally shortened during these operations to permit die 22, or its equivalent, directly to apply some longitudinal pressure to tube 20, as an aid to the mentioned inward buckling thereof.

75 It will be seen that the compressed mica "washers," or their equivalent, are retained under a desired high pressure because the collapsing of the weakened section is accomplished in such manner as to avoid any inequality of compression,—this effect, in turn, being due to the fact that only the constricted 130

portion of the shell 21 is highly heated, the pressure to which the mica "washers" are subject being controlled according to the pressure and temperature at which the weakened portion will so collapse as substantially to diminish the electrical resistance thereof and/or by a longitudinal shortening of the shell 21,—and the contraction of metallic parts in cooling to normal room temperature being, in any case, effective not only to maintain but to increase the pressure under which the mica, or its equivalent, is held.

As diagrammatically suggested in Figs. 3 and 4, one of a pair of contact elements 24', 24" may be so positioned that a predetermined downward advance of the die element 22, or its equivalent, to produce an inward buckling of the weakened section 21c, automatically effects a discontinuance of current therethrough; and it will be understood that the mentioned method and/or the mentioned use of the brass tube 20, or its equivalent, prevents any such bulging of the shell 21 as might cause the same to project and cut through the mica sleeve 18, or its equivalent. The clamping pressure exerted by the described steps, including the shrinking of the resultant annular rib of the shell 21 (which rib commonly unites, as by welding, to the tube 20) has been found to be such that a hammer will not drive off or loosen the grip of the mentioned outer parts, herein-after referred to as mica assembly A, upon the rod or wire 15.

The wire or rod 15 is shown as provided additionally with an upper or outer mica assembly B, comprising a third insulating element 22', adapted to fit over the sleeve 18, and a fourth insulating element 22", the latter having a central aperture so restricted as to fit directly and snugly upon the wire or rod 15, and the last-mentioned element being shown as retained by a final stop or clamping element 25. The general construction of the clamping element 25 and the method of positioning and securing the same may be substantially the same as above described in connection with the shell 21.

That is to say, the clamping or "nut" element 25 is shown as provided with a comparatively deep kerf 25', with the result that comparatively wide and rugged portions 25a, 25b thereof are connected by a weakened portion 25c having a reduced cross-section and comparatively high electrical resistance, so that a suitable application of pressure, as by means of a so-called die element 26, may be relied upon to so deform the clamping element 25, producing an inward bulge in the region of the weakened section 25c (through which an electrical current may be passed in the indicated manner) as permanently to secure said clamping element (assumed initially to have a smooth bore) upon a threaded

or other portion of the wire or rod 15, or its equivalent. The threads aid welding.

It will be obvious that if desired, the insulating element 22', even if formed of superimposed mica "washers," might serve as the mentioned die elements 22, the insulating assemblies being either successively or simultaneously secured in the general manner described; but it is ordinarily deemed preferable separately to execute the described operation—employing the die 26 in connection with a cooperating die (shown as adapted to engage the non-circular portion 21a of the shell 21) and adapting the die 26, flat or of a configuration indicated at 26', to impart some inward pressure incidentally to the application of longitudinal pressure thereby. The result may be a partial fusing or welding union between the rod or wire 15 and the clamping nut 25, in substantially the general manner suggested in Fig. 7, upon thermoplastic deformation.

An inner electrode spindle, formed in the general manner described, may obviously be incorporated in a so-called one-piece spark plug or in a so-called two-piece spark plug—a form of the latter being shown in Fig. 1 as comprising a conductive body which is internally threaded at 28 for engagement with the mentioned shell 21 and as externally threaded at 29 in a known manner—a gas-retaining gasket being shown as interposed at 30; and the externally threaded portion 29 may be provided with a suitably positioned and spaced electrode element having either the blunt-wedge configuration suggested at 31, Figs. 1 and 8, or a substantially hemispherical or uniformly rounded configuration, somewhat as suggested at 31', Fig. 9,—the latter being presumably the more durable, and the former better adapted to certain specific conditions of use, as will be understood by workers in this field.

Under certain conditions, pressure without electric heat may be employed in the above process; and it will be obvious that, according to circumstances, either or both of a pair of stop or binding elements comparable with 16 and 21 or 21 and 25 or 16 and 25 (at least one of said stop elements being initially annular and movable), may be secured to some central tensionable element such as the wire or rod 15, after an appropriate application of pressure therethrough to intermediate laminæ or other assemblies or units; that when separate assemblies of laminæ, or like insulating parts are to be used in contact with an intermediate shell 21, or its equivalent (as in the case of assemblies A and B, shown as formed from outer or small-opening sections 17 and 22" having associated therewith large-opening sections 19 and 22') they may be externally provided with a desired taper, or with any special configuration and/or polish either before or

after (but preferably after) being permanently bound in the described general manner; that any of the mentioned parts (as end pieces 25) may be cut and/or polished incidentally to machining and like operations; that any interior use of cement or softenable insulating materials (somewhat as suggested at 32 and 32' in Figs. 3 and 4, and as suggested at 33 and 33' in Figs. 5 and 6) should be regarded as ordinarily unnecessary; and that the tube 20, when used, may well have a length intermediate between the initial length and the final length of the shell 21; but, if formed of mica or a similar material, the sleeve 18, when used, should be of such length as to leave a clearance space 34 at one end thereof. A lustrous and exceedingly durable product results,—not subject to leakage, chipping or warping.

Referring further to features which are entirely optional, one or both of a co-operating pair of die or pressure elements (as, the element 23) may be advanced or supported by means including some pressure-responsive element,—as symbolized in Fig. 4 by a spring 35; and the wiring details schematically shown in Fig. 4 and 6 will respectively suggest that the breaking of a contact, as at 24', Fig. 6, may result either from a predetermined shortening of an applied clamping element or from the attainment of a predetermined maximum pressure thereon, and that, in either case, a discontinuance of current through any pressure-applying means may be incidentally effected; but it will be understood that the arrangement shown in Fig. 6 differs from that shown in Fig. 4 in requiring or permitting some conduction through the rod 15; that alternative means may be employed, in preference to the spring 35 (yielding under a predetermined pressure—say one ton per square inch) to support a part such as inner insulation assembly A during a compression thereof and yet to obviate risk of damage thereto during the employment of a higher pressure (say, two tons per square inch) to effect a slightly subsequent and inward deformation of an annular retaining element; that, to assure an enhanced and permanent compression by contraction upon cooling, electrical heating, when employed, should be discontinued before the dies are permitted to separate; that the principles of this invention are by no means limited to the production of the disclosed double-insulated inner electrode assembly or unit; that either the conductive stem or rod 15 or a collapsible element disposed thereon may be provided with threads or other projections adapted to be partially stripped to assure good contact and reliable retention; that, although threads thereon adapt the outer end of the rod 15 to carry an additional nut or nuts, to engage conductors in a known manner, and the described pro-

cedure obviates such relative rotation of any "nut" 25 as might tend toward distortion of the outer insulation assembly B, said "nut" may have any desired alternative form; that the head 16 and the "nut" 25, or equivalent terminal stop or retaining elements differ from the intermediate retaining element 21 in that one of the former may be, and both of them preferably are in the finished unit, integral with the stem or rod 15; that sole reliance upon the welded nut 25 is not recommended; and that a permanently high longitudinal tension and a high radial compression of the central wire or rod 15 or its equivalent, may conveniently be assured by a proper execution of the described compression and heating steps in some electrical welding machine of a known type.

Although the foregoing description has included complete details of but one embodiment of the present invention, various alternatives being incidentally suggested, it should be understood not only that various features thereof may be independently employed but that numerous modifications, additional to those mentioned herein, might easily be devised,—without involving the slightest departure from the spirit and scope of this invention.

I claim:

1. A method of placing a part under compression upon a rod-like element and securing a pressure-maintaining annular element thereon which comprises: so weakening said annular element by a peripheral groove as to adapt a region thereof to inward distortion under longitudinal compression; and applying thereto such longitudinal pressure as first to compress said part to the desired degree and then inwardly to distort said region into a nonslipping engagement with said rod-like element.

2. A method of placing a part under compression upon a rod-like element and securing a pressure-maintaining annular element thereon which comprises: so weakening said annular element by a peripheral groove as to adapt a region thereof to inward distortion under longitudinal compression; and applying thereto such longitudinal pressure as first to compress said part to the desired degree and then inwardly to distort said region into a nonslipping engagement with said rod-like element, sufficient heat being applied to one of said elements, during said application of pressure thereto, to soften said region.

3. A method of placing a part under compression upon a rod-like element and securing a pressure-maintaining annular element thereon which comprises: so weakening said annular element by a peripheral groove as to adapt a region thereof to inward distortion under longitudinal compression; and applying thereto such longitudinal pressure

as first to compress said part to the desired degree and then inwardly to distort said region into a nonslipping engagement with said rod-like element, sufficient heat being applied, by means of an electrical current, to soften said region while said pressure is maintained.

4. A method of placing a part under compression upon a rod-like element and securing a pressure-maintaining annular element thereon which comprises: so weakening said annular element as to adapt a region thereof to inward distortion under longitudinal compression; and applying thereto such longitudinal pressure as first to compress said part to the desired degree and then inwardly to distort said region into a nonslipping engagement with said rod-like element, one of said elements being threaded.

5. A method of securing an insulating sleeve between a rod-like element and a tube which comprises: surrounding said tube by an annular element having a pre-weakened region thereof adapted as to permit of its distortion under longitudinal pressure; and applying thereto such longitudinal pressure as to produce, by an inward distortion in said region, an annular constriction in said tube.

6. A method of securing an insulating sleeve between a rod-like element and a tube which comprises: surrounding said tube by an annular element having a pre-weakened region thereof adapted as to permit of its distortion under longitudinal pressure; and simultaneously applying thereto sufficient heat to soften the same and such longitudinal pressure as to produce, by an inward distortion in said region, an annular construction in said tube.

7. A method of securing an insulating sleeve between a rod-like element and a tube which comprises: surrounding said tube by an annular element having a region thereof so weakened as to permit of its distortion under longitudinal pressure; and applying thereto such longitudinal pressure as to produce, by an inward distortion in said region, an annular constriction in said tube, said region being a region having a relatively restricted cross section and high resistance, and said heating being effected by passing electricity therethrough.

8. A method suitable for use in providing a central tensionable element carrying a stop element with an assembly of mica insulation which comprises: so disposing the assembly upon said tensionable element as to be retained by said stop element; disposing a metallic shell element provided with a weakened region upon said assembly; compressing said assembly between said stop element and said shell element; and so inwardly distorting said weakened region as to prevent subsequent slippage of parts relatively to said conductive element.

9. A method as defined in claim 8 in which, an insulating sleeve and a tube being disposed between said tensionable element and said shell, the mentioned distortion is so executed as to produce a constriction in said tube, compressing said sleeve between said tube and said tensionable element.

10. In the production of substantially gas-tight spark plugs, a method characterized by the fact that a metallic element which has nonvitreous insulation disposed therein is given such an internal diameter while hot as radially to compress said insulation upon cooling.

11. A method as defined in claim 10 in which a protecting tube is interposed between said metallic element and said insulation in advance of said deformation.

12. A spark plug spindle comprising: an inner electrode, mica sleeve insulation and mica washer insulation thereon; and retaining elements therefor including a metallic intermediate element and a metallic terminal element, one of said metallic elements having been heated under a mica-compacting pressure and thermoplastically collapsed axially thereof for a retaining effect.

13. For use in an article of the general character set forth: a thermoplastically collapsible retaining element comprising a body provided with an annular external channel, defining a zone which is adapted initially to transmit a compressive thrust and later to undergo a collapse,—to exert sealing and retaining effects both when hot and on cooling.

14. A double-insulated inner-electrode spark plug unit comprising: a tensionable electrode; and an inner insulation assembly and an outer insulation assembly secured thereon under compression by means comprising a collapsed retaining element insulated from, but secured against longitudinal movement upon said stem.

15. An article of manufacture comprising: a tensionable element provided with a shouldered stop; an insulating assembly of mica on said tensionable element; and a retaining element permanently welded to said tensionable element at such a distance from said stop as to secure said insulating assembly under high compression between said stop and said retaining element.

16. For use in an article of the general character set forth in claim 15: a retaining element in the form of a shell comprising a threaded portion and a noncircular portion separated by a weakened region which is adapted to be inwardly distorted under pressure.

17. The method of assembling spark plugs which includes the disposition about a compressible insulator sleeved on an electrode of an annular retainer element having a prepared collapsible region, and the application

of longitudinal pressure on said retainer element to shorten the length thereof by the collapse of said region so as to exert a radially inward compression of the insulator sleeve.

5 18. The method of securing to a rod-like part an apertured member having a reduced neck portion, which includes inserting the rod-like part through the aperture of the member, then heating said neck portion to 10 soften the same, and placing axial pressure on the member to collapse the softened neck and contract the aperture.

15 19. The method of assembling spark plugs or the like, which includes inserting an electrode in an insulator sleeve, surrounding the sleeve with an annular retainer having a reduced neck, heating said neck to soften the same and placing endwise pressure on the retainer to axially collapse the softened neck 20 and thereby form an interior bulge that compacts the sleeve about the electrode.

25 20. The method of assembling spark plugs, which includes placing insulation on an electrode, and applying pressure on a retainer element to first compact longitudinally a portion of the insulation and then deform the element to compact radially another portion of the insulation and to bind the retainer element in position on the electrode.

30 21. The method of assembling spark plugs, which includes interposing a body of compressible insulation between an abutment on an electrode element and an annular element sleeved on the electrode element, compressing said insulator body between the abutment and annular element, heating a portion of the annular element to soften the same, and applying axial pressure on said element to collapse the heated portion thereof, into a 35 40 locking relation with the electrode element.

22. The method of assembling spark plugs, which includes interposing a compressible insulator body between a stop carried by the central electrode and a retainer element fitted to the electrode, compressing said insulator body and then molecularly uniting the retainer element and electrode to permanently maintain the insulator body under compression.

45 23. The method of assembling spark plugs, which includes interposing a compressible insulator body between a stop carried by the central electrode and a retainer element fitted to the electrode, applying endwise pressure to said retainer to axially compact said insulator body, and applying heat to a portion of the retainer to soften the same for collapse under endwise applied pressure so as to fix it to the electrode and thus maintain 50 55 60 the insulator body under permanent compression.

In testimony whereof I affix my signature,
HECTOR RABEZZANA,
